COMBINED DESK AND BOOK RACK

Yoshio Deguchi, Tokyo, and Fumio Yanaguchi, Yokohama, Japan, assignors to Okamura Manufacturing Company Limited, Yokohama, Japan

Filed Dec. 11, 1969, Ser. No. 20,449

Claims priority, application Japan June 23, 1969

Term of patent 14 years

Int. Cl. D6—06

U.S. Cl. D33—7

FIG. 1 is a front view of a combined desk and book rack embodying our design;

FIG. 2 is a back view of the combined desk and book rack;

FIG. 3 is a plan view of the combined desk and book rack;

FIG. 4 is a bottom plan view of the combined desk and book rack;

FIG. 5 is an elevational view showing one of the two identical sides of the combined desk and book rack;

FIG. 6 is a vertical sectional view of the article taken along the line 6—6 of FIG. 1; and

FIG. 7 is a front perspective view of the combined desk and book rack showing the drawer member thereof in extended position.

We claim:

The ornamental design for a combined desk and book rack, as shown and described.
